UNITED STATES PATENT OFFICE.

WINFIELD S. NELSON, OF COMMERCE, OKLAHOMA.

DINNER PAIL.

Application filed June 9, 1922. Serial No. 566,998.

To all whom it may concern:

Be it known that I, WINFIELD S. NELSON, a citizen of the United States, residing at Commerce, in the county of Ottawa and 5 State of Oklahoma, have invented certain new and useful Improvements in Dinner Pails; and I do hereby declare the following to be a full, clear, and exact description of the invention, such as will enable 10 others skilled in the art to which it appertains to make and use the same.

This invention relates to a container for food and drink, whereby various articles of food may be carried in a single receptacle 15 such as a bucket or pail and be kept entirely separated without mixing and in which the bail when in upright or carrying position is positively held from swinging, and which bail in turn operates as locking means for 20 securing the cover on the container against possible displacement, said bail when lowered into inoperative position automatically releasing the cover which may be removed or replaced as required.

25 Other objects and advantages will be apparent and suggest themselves as the nature of the invention is understood.

While the drawings illustrate an embodiment of the invention it is to be understood 30 that in adapting the same to meet different conditions and requirements, various changes in the form, proportion and minor details of construction may be resorted to without departing from the nature of the invention.

35 Referring to the accompanying drawings forming a part of the application,

Figure 1 is a perspective view of a dinner pail embodying the invention, the bail being lowered into inoperative position,

40 Figure 2 is a vertical central longitudinal section of the article, the bail being elevated into carrying position,

Figure 3 is a horizontal section on the line 3—3 of Figure 2,

45 Figure 4 is an elevation of one of the ears and parts of the pail, cover and bail showing the same on a larger scale,

Figure 5 is a top plan view of the parts shown in Figure 4, and

50 Figure 6 is a sectional detail on the line 6—6 of Figure 4, the full lines showing the bail elevated and in locking engagement with the cover, and the dotted lines illustrating the position of the bail when lowered and disengaged from the cover.

Corresponding and like parts are referred to in the following description and designated in the several views of the drawings by like reference characters.

The container comprises a bucket or pail 60 1 which is preferably, though not necessarily, of oval contour in plan view.

A vessel 2 of corresponding shape is suspended within the upper portion of the pail 1 and is of less depth than said pail so as 65 to leave the space 3 which constitutes a compartment for a beverage or drink such as coffee. The bottom of the vessel 2 constitutes a cover for the compartment 3. The vessel 2 tapers slightly throughout its length 70 to facilitate its entrance and removal from the pail 1. The upper edge of the vessel 2 is outwardly rolled or beaded as indicated at 4 so as to extend over the upper edge 75 of the pail 1 and support the vessel therein.

A sectional tray is adapted to be placed within the lower portion of the vessel 2 and comprises similar or like sections 5 each divided to form compartments 6 which are adapted to receive edibles of different 80 varieties such as meat and vegetables or fruit.

If preferred for any reason, the sections 5 comprising the food tray, may be placed one upon the other thereby leaving a space 85 at one side for bread, fruit or other article. A shallow tray 7 is adapted to be suspended within the upper portion of the vessel 2 by means of an outer roll or flange 8 at its upper edge engaging over the beaded edge 4 90 of the vessel 2. The tray 7 is adapted to receive a delicacy such as pie, cake or the like. The pail is adapted to be closed by means of a cover 9 whose depending rim has an outer flange, bead or roll 10. The cover 9 is provided with a handle 11 for convenience of 95 manipulation thereof.

Ears 12 are attached to opposite sides of the pail 1 near the top thereof and receive a bail 13. The ears project above the pail and the upper portion of each has a vertical groove 14 in its outer side to receive an end portion of the bail adjacent the inturned end or pivot 15 thereof. The upper end of each side portion of the ear bordering upon the groove 14 is inclined as indicated at 16 for the end portion of the bail 13 to ride upon when swinging the bail from vertical or upright position into lowered or inoperative position whereby to draw the inturned or 100 105 110

pivot ends 15 outwardly so as to clear the outer flange, bead or roll 10 at the lower edge of the cover, whereby the latter may be placed in position or removed from the pail as required. The inturned or pivot ends 15 of the bail pass through openings 17 of the ears and are adapted to engage over the outer extension 10 of the cover 9 when the bail is in upright or carrying position where-
10 by to lock the cover upon the pail against casual displacement. The bail 13 is formed of stout spring wire and its pivot ends 15 normally tend to spring inwardly so as to engage over the outer extension 10 of the cover. When the bail is in upright or carrying position, the end portions adjacent the pivot 15 are seated in the vertical grooves 14, thereby maintaining the bail in upright and locking position. When the bail is
15 swung from upright position into lowered or inoperative position, the end portions ride upon the inclined edges 16 of side portions of the ears, thereby spreading the bail and withdrawing the pivots 15 from engagement
20 with the outer extension 10 of the cover so that the latter may be readily removed or placed in position as required. The ears 12 are preferably formed from stout plate metal and are struck or stamped therefrom, the
25 upper portion being folded so as to provide the vertical groove 14 between the wings or folded portions constituting the sides which are spaced to form the grooves.

What is claimed is:

1. A dinner pail comprising a container, a vessel removably fitted within the upper portion of the container and tapering in its length to facilitate removing or placing the vessel in position and having an outer roll or extension at its upper edge to engage over the upper edge of the container to support the vessel therein, and a tray removably fitted within the upper portion of the vessel and having an outer bead or extension to overlap the upper edge of the vessel and support the tray therein. 35 40 45

2. A dinner pail comprising a container, a cover therefor having an outer extension, ears attached to opposite sides of the container and projecting above the same and having vertical grooves in their outer sides, and the upper edges of the side walls inclined, and a spring a bail having inturned pivot ends engaging the ears and adapted to engage over the outer extension of the cover 55 and secure the latter when the bail is in upright position, said pivot ends being withdrawn from engagement with the cover when lowering the bail and the riding of the ends thereof on the inclined ends of the ears. 60

In testimony whereof I affix my signature in presence of two witnesses.

WINFIELD S. NELSON.
